UNITED STATES PATENT OFFICE

LOUIS SIMON FRAPPIER AND EWALD BOECKING, OF BROOKLYN, NEW YORK, ASSIGNEES
TO INTERNATIONAL PROJECTOR CORPORATION, OF NEW YORK, N. Y., A CORPORATION OF DELAWARE

TELESCOPE FRAMING DEVICE

Application filed June 29, 1929. Serial No. 374,761.

This invention relates to projection machines, and more particularly to a machine having mechanism for scanning a photographic sound record. The invention provides for supporting a microscope in the path of a scanning ray in such position that the ray can be observed while adjustments are being made to secure the proper characteristics thereof.

10 An object of the invention is to provide a simple support for the microscope which may be readily secured to the machine and held in a fixed position while the adjustments are being made.

15 Another object is to utilize existing portions of the machine for supporting the microscope.

A still further object is to provide a support for the microscope which can be utilized without disturbing the adjustment of the machine.

The invention is particularly applicable to a projection machine having a sound film gate which is slidably supported thereon. 25 In this type of machine provision is made for removing the film gate and attaching the microscope to the film gate support in a position to intercept the rays of the scanning light. Provision is also made for mounting the microscope on the aperture plate without removing the film gate.

The invention also consists in certain new and original features of construction and combinations of parts hereinafter set forth 35 and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is an elevation of a projection head showing the location of the various parts;

50 Fig. 2 is an elevation of the sound reproducing apparatus showing the telescope and photo-electric cell;

Fig. 3 is a plan view of the sound reproducing apparatus and associated mechanism;

Fig. 4 is a side elevation of the film gate in closed position;

Fig. 5 is a section taken on the line 5—5 55 of Fig. 3;

Fig. 6 is an elevation partly in section of the aperture plate and microscope support;

Fig. 7 is a section taken on the line 7—7 60 of Fig. 6 showing the aperture plate;

Fig. 8 is a plan view partly in section of the microscope and supporting mechanism;

Fig. 9 is a section taken on the line 9—9 of Fig. 8;

Fig. 10 is a side elevation of the film gate 65 in open position showing the microscope supported by the aperture plate;

Fig. 11 is an enlarged detail view of the film gate in closed operating position;

Fig. 12 is a plan view of the microscope 70 showing the mechanism for supporting the same from the aperture plate; and

Fig. 13 is an enlarged detail of the supporting bracket.

Like reference characters denote like parts 75 in the several figures of the drawings.

In the following description and in the claims parts will be identified by specific names for convenience, but they are intended to be as generic in their application to similar parts as the art will permit.

Referring more particularly to the drawings, the invention is shown as applied to a projection head (Fig. 1) including an upper film magazine 10, upper film gate 11, sound film gate 12 and associated sprockets for feeding a film successively over said film gates. The apparatus is adapted to project a picture on a distant screen and at the same time scan a photographic sound record which may be incorporated on the projection film. It is to be understood, however, that the sound apparatus described herewith is not limited to use with a projection machine but is only shown associated therewith by way of illustration.

A suitable apparatus for directing light rays upon a sound record is shown in Fig. 2 as including a pair of light sources 20 which may be selectively brought into alignment 100

with telescope 21. Said telescope receives rays from light source 20 and directs said rays on aperture plate 22. When film gate 12 is closed (Fig. 4) film 13 is held in engagement with said aperture plate and is passed thereover by means of continuous sprocket 23 which is driven by any suitable mechanism. The light rays from telescope 21 are directed through aperture plate 22, through the sound record on film 13 and are impressed upon photo-electric cell 24 which is housed in a suitable compartment 25. Only so much of the scanning mechanism will be described as is necessary to an understanding of the present invention. One type which may be employed is described more in detail in the copending application of Frappier & Boecking, Serial No. 303,162, filed August 31, 1928, for improvements in projection machine.

Film gate 12 comprises a pressure shoe 30 which is held in engagement with the aperture plate and pressure shoes 31 and 32 which are held in engagement with continuous sprocket 23 and idler sprocket 33 respectively. These members are supported on a bracket 34 which is dovetailed for sliding movement on wall 35 forming a portion of the closure for the photo-electric cell compartment 25. For this purpose member 34 is provided with a groove which cooperates with a tongue 36 on said wall. Suitable locking means such as grooved rod 37 may be provided for holding the parts in their desired position. A handle 38 is associated with the film gate for controlling the position thereof. Film gate 12 may be removed after the gate has been brought into open position as shown in Fig. 10 by releasing the locking means 37 and 40 sliding the bracket 34 over tongue 36.

The microscope comprises a tube 40 (Fig. 8) carrying the usual lenses 41 and supported in a collar 42 which is secured in housing 43 by suitable means such as set screw 44. Housing 43 is secured to strap 45 (Fig. 9) by a screw 46 and is slidably secured to a bracket 50 by set screw 51 which is threaded in said bracket. The vertical position of strap 45 is controlled by thumb screw 54 which is threaded into horizontal ear 55 formed on said strap and contacts with the upper surface of bracket 50. Strap 45 is provided with an elongated hole 52 to permit vertical adjustments with respect to screw 51 and bracket 50.

Bracket 50 is provided with a suitable groove to engage tongue 36 on wall 35 and may be slidably secured thereon. Grooved rod 56 is held in a suitable recess in bracket 50 and is provided with a down-turned handle 57 (Fig. 9) through which screw 58 is threaded, bearing against a shoulder 59 on bracket 50 for rotatably moving rod 56 and bringing the notched portion thereof into engagement with tongue 36.

Housing 43 is provided with a tubular bore 60 having openings 61 and 62 communicating with telescope 40 and aperture 64 of aperture plate 22 respectively. A barrel 65 (Figs. 5 and 6) is formed to fit within bore 60 of housing 43. Said barrel is provided with upper and lower bearing sections 66 and 67 respectively, and a triangular prism support 68 (Figs. 5 and 8) positioned therebetween. Prism 69 may be secured to said prism support by means of straps 70 which engage said prism and are secured to said support by screws 71.

Housing 43 is formed of a suitable size to engage film guides 73 of aperture plate 22 when the apparatus is in operative position. For securing a fine adjustment of bracket 50 with respect to tongue 36 there is provided a screw 80 (Fig. 8) which is threaded into said bracket and is provided with a head 81 which is brought into engagement with tongue 36.

Barrel 65 is provided with a knurled extension 75 to provide a hand grip for making the necessary adjustments. Said barrel is also provided with a pair of oppositely disposed shoulders 76 engaging screws 77 which are held in housing 43 whereby the barrel is secured in the desired adjustment. A slight rotational movement of said barrel 95 may be effected by the proper manipulation of screws 77 whereby pressure is exerted on one of said shoulders 76 and pressure on the other of said shoulders is relieved.

To align the microscope with the aperture plate, the film gate is first removed in a manner pointed out above, and housing 50 is brought into sliding engagement with tongue 36, and is adjusted by screws 80 until the proper alignment of aperture 63 and aperture 64 is obtained. The bracket may then be locked by rotating handle 57 to bring rod 56 into engagement with said tongue. Vertical adjustment of housing 43 is obtained by loosening set screw 51 and manipulating thumb screw 54 so that the required alignment is obtained. Barrel 65 may then be rotatably adjusted by means of screws 77 to so position the apparatus that light rays passing through aperture 64 are deflected by means of prism 69 and focused through lenses 41 in telescope 40. The light rays may accordingly be observed through said microscope while the necessary adjustments thereof are being made. These adjustments 120 will ordinarily involve the positioning of light source 20 in the proper alignment with telescope 21 and will be required only once for each light source. After the various light sources have been adjusted the microscope may be removed by rotating rod 56 and thereby releasing bracket 50 from tongue 36, after which the film gate may be returned to its operative position.

A modified form of support for the micro-

scope 40 which does not require the removal of film gate 12 is shown in Figs. 10, 12 and 13. This support comprises a bracket 90 (Fig. 12) which is provided with a horizontal extension 92 which is adapted to bear against film guides 73 and 74 of aperture plate 22. Bracket 90 is threaded to barrel 93 which is adapted to engage aperture 64 in aperture plate 22. Bracket 90 is extended to form a sleeve 94 in which microscope 40 may be secured and is provided with a suitable clamp 95 for securing prism 69 thereto.

To apply the microscope to the aperture plate it is only necessary to open film gate 12 and remove telescoping members 96 from telescope 21. Bracket 90 is then brought into the position shown in Fig. 12 and barrel 93 turned to bring the same into firm engagement with aperture plate 22. Extension 92 of bracket 90 contacting with film guides 73 and 74 serves to secure the microscope in position.

It is to be noted that in the apparatus above described the microscope may be readily brought into operative position for adjusting the rays of the scanning light and is supported in operative position while such adjustment is being made. By mounting the microscope on the support for the film gate the use of a separate device for supporting the microscope is avoided. In the arrangement shown in Figs. 10, 12 and 13 the microscope may be adjusted without removing the film gate and is secured directly to the aperture plate itself. This type of support may be desirable under certain conditions and may be used with film gates which are not readily removable.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In a machine for producing sound from a photographic sound record, means for producing a scanning light, a film gate for directing said sound record past said light, a support therefor, and a microscope for facilitating adjustment of said light, means for supporting said microscope comprising a housing having an aperture therein, a prism supporting means mounted adjacent said aperture for changing the angle of the scanning light, and means for mounting said housing upon said film gate support interchangeably with said film gate.

2. In combination with a photographic sound reproducing mechanism including a light source, aperture plate and photoelectric cell, a microscope for adjusting said

mechanism, said microscope carrying a light deflecting member, means for mounting said microscope between said light source and said photoelectric cell with its axis at approximately right angles to the axis of the scanning ray and with said deflecting member in the path of said ray whereby said ray is deflected and focused in said microscope to permit adjustment of said ray without removing the photoelectric cell.

3. In a photographic sound reproducing apparatus including means for producing a scanning ray, a photographic sound record, a film gate for directing said record past said scanning ray, a support for said film gate and a microscope for facilitating adjustment of said ray, and means for supporting said microscope upon said film gate support interchangeably with said film gate.

4. In combination with an apparatus for scanning a photographic sound record including a film gate and a support therefor, a microscope, a housing carrying said microscope, a light deflecting member mounted in said housing and adapted to direct the scanning light into said microscope, means for mounting said microscope on said film gate support comprising a bracket slidably secured to said support, a strap slidably secured to said bracket and carrying said housing, and means for causing relative adjustment between said strap and said bracket and between said bracket and said support.

5. In combination with a microscope, a housing supporting said microscope, means on said housing for supporting a prism in a position to deflect rays of light at right angles into said microscope, a strap carrying said housing, a bracket, means for slidably mounting said strap on said bracket for vertical movement, a support, means for slidably mounting said bracket on said support for horizontal movement, and means for angularly adjusting said prism support with respect to the axis of said telescope.

6. In a machine for scanning a photographic sound record, an aperture plate for directing a scanning light onto said sound record, a microscope, means for mounting said microscope with its axis at substantially right angles to the scanning light, a light deflecting member for deflecting said scanning light along the axis of said microscope, means for mounting said microscope adjacent said aperture plate, and means for adjusting said microscope vertically and horizontally with respect thereto for bringing said light deflecting means into alignment with said scanning light.

7. In a machine for scanning a photographic sound record, an aperture plate for directing a scanning light on to said record, a microscope for viewing said rays, means for supporting said microscope from said aperture plate comprising a bracket supporting

said microscope, and means for clamping said bracket to said aperture plate.

8. In a machine for scanning a photographic sound record, an aperture plate for directing a scanning light on to said record, a microscope for viewing said rays, means for supporting said microscope from said aperture plate comprising a bracket supporting said microscope, and means for clamping said bracket to said aperture plate, said clamping means comprising a tubular member adapted to be positioned in the path of the scanning rays and to permit passage of said rays therethrough.

15 9. In combination with a motion picture projection machine, a device associated therewith for scanning a photographic sound record, mechanism for facilitating adjustment of said scanning mechanism, a film gate for directing said photographic record past said scanning mechanism, and a single support carrying interchangeably said adjusting mechanism and said film gate.

LOUIS S. FRAPPIER.
EWALD BOECKING.
